US0D1099670S

(12) **United States Design Patent** (10) Patent No.: **US D1,099,670 S**
(45) Date of Patent: ** Oct. 28, 2025

(54) **COAT PEG**

(71) Applicant: **PVH Production A/S**, Ribe (DK)

(72) Inventor: **Martin Sonne**, Ribe (DK)

(**) Term: **15 Years**

(21) Appl. No.: **35/522,398**

(22) Filed: **Aug. 29, 2024**

(80) **Hague Agreement Data**

Int. Filing Date: **Aug. 29, 2024**

Int. Reg. No.: **DM/239971**

Int. Reg. Date: **Aug. 29, 2024**

Int. Reg. Pub. Date: **Sep. 20, 2024**

(30) **Foreign Application Priority Data**

Mar. 1, 2024 (EM) 015050250-0003

(51) **LOC (15) Cl.** **08-06**

(52) **U.S. Cl.**

USPC **D8/310**

(58) **Field of Classification Search**

USPC D2/853; D6/320, 323; D8/310

CPC A47G 25/0607
